UNITED STATES PATENT OFFICE.

JOSEPH C. BEERY, OF KANSAS CITY, MISSOURI.

MUFFLER CONSTRUCTION.

Application filed August 4, 1927. Serial No. 210,694.

This invention relates to muffler constructions and more particularly to the construction of a combined muffler and cut-out.

An important object of the invention is to improve the structure of my prior Patent, No. 1,615,564, granted January 25, 1927, for combined muffler and cut-out.

A further and more specific object of the invention is to provide an improved muffler construction whereby the sound emanating from the muffled exhaust is materially reduced.

A still further object of the invention is to provide a structure including a plurality of muffling valves, such as shown in the prior patent above identified, wherein one of these valves is so constructed that it serves not only its muffling function, but likewise serves to maintain the muffling valves in their muffling position.

These and other objects I attain by the construction shown in the accompanying drawings, wherein for the purpose of illustration is shown a preferred embodiment of my invention and wherein:—

Figure 1 is a longitudinal sectional view through an exhaust pipe and muffler constructed in accordance with my invention;

Figure 2 is a section on the line 2—2 of Figure 1;

Figure 3 is an enlarged detail view showing the different arrangement of the conducting tubes employed in the intermediate shell.

Referring now more particularly to the drawings, the numeral 10 generally designates an exhaust tube having adjacent its rear end a circumferential series of openings 11. Surrounding the exhaust pipe are front and rear heads 12 and 13 which are substantially identical with the exception of the fact that the rear head has adjacent its periphery, as indicated at 14, an exhaust opening, through which the muffled exhaust gases may pass. Adjacent faces of the heads have recesses 15 receiving the ends of a sleeve 16, which is of slightly greater diameter than the exhaust tube, so that a chamber 17 is formed between the exhaust tube and sleeve. A cover or outer shell 18 has its ends suitably secured to the peripheries of the heads 12 and combines with the sleeve 16 to produce an annular chamber 19. The rear head 13 is secured upon the exhaust tube 10 adjacent the annular series of openings and between this series and the end of the tube, while the head 12 is well spaced therefrom. Adjacent the

head 12, the sleeve 16 is provided with openings, the edges of which are defined by tubes 20, which may extend either inwardly or outwardly from the tube, as illustrated in Figures 1 and 3 respectively. It will be obvious that exhaust gases, if obstructed from passage through the rear end of the exhaust tube, will pass through the openings 11, entering the annular chamber 17 near the rear end thereof and moving to the forward end thereof where they pass through the tubes 20 into the forward end of the annular chamber 19. Moving rearwardly through this chamber, they pass to the atmosphere through the exhaust opening 14. It has been found that the tubes 20 serve to materially increase the muffling effect which is obtained by the use of a similar structure in which ordinary openings are provided through the shell, since they prevent the Venturi action resulting from the formation of an opening through thin metal.

The exhaust tube 10 has arranged therein a rear or control valve 21 and a pair of forward muffling valves 22 and 23, the valve 22 being arranged rearmost. Each of the valves 21, 22 and 23 is of the butterfly type and arranged upon aligned parallel pivots. The valve 22 is perforated for the passage of exhaust gases, so that the space between this valve and the valve 21, when the valves are in the closed position, acts as a central muffler chamber. The valve 23 is fragmentary, being in reality only one-half of a butterfly type valve. Gases moving longitudinally of the tube 10 from the intake toward the exhaust end thereof will exert pressure to move the valve 23 from the open to the closed position. The pivot stems of the valves 21, 22 and 23 have operating arms 24 which are connected for simultaneous movement by a rod 25 which may be in turn connected to an operating element 26.

It will be obvious that when the valves 21, 22 and 23 are moved to the open position, the pressure of gases against the fragmentary valve will constantly urge the same to closed position. Since the pressure upon the valves 21 and 22 will be balanced at opposite sides of the pivot, it follows that this pressure will act to move all of the valves to closed position, thus eliminating the necessity of a relatively heavy spring for accomplishing this function. It is pointed out that heavy springs resisting the movement of the valves render operation of the cut-out difficult and the device unsuitable for applica-

tion to cars which are driven by women. It is pointed out that the valve element 23 not only acts to assist in the closing operation, but likewise functions when in closed position as a baffle combining with the valve 22 to produce a muffler chamber within the exhaust tube, thus further reducing the noise of the escaping exhaust gases.

Since the construction hereinbefore set forth is capable of a certain range of change and modification without materially departing from the spirit of the invention, I do not limit myself to such specific structure except as hereinafter claimed.

15 I claim:—

1. In combination, an exhaust tube, a muffler communicating with the tube intermediate the inlet and outlet ends of the tube, a valve between the point of communication and the outlet of the exhaust tube and in one position thereof closing the tube, a second valve between the point of communication and the inlet of the exhaust tube and in one position thereof partially closing the tube, an element within the tube, a connection between said valves and element whereby upon movement of the element in one direction the valve will move to closed position, said element being constantly urged by the passage of exhaust gases through said tube in said direction.

2. In combination, an exhaust tube, a muffler communicating with the tube intermediate the inlet and outlet ends of the tube, a valve between the point of communication and the outlet of the exhaust tube and in one position thereof closing the tube, a second valve between the point of communication and the inlet of the exhaust tube and in one position thereof partially closing the tube, an element within the tube, a connection between said valves and element whereby upon movement of the element in one direction the valve will move to closed position, said element being constantly urged by the passage of exhaust gases through said tube in said direction, said element combining with the last named valve to produce a muffler chamber.

3. In combination, an exhaust tube, a muffler communicating with the tube intermediate the inlet and outlet ends of the tube, a valve between the point of communication and the outlet of the exhaust tube and in one position thereof closing the tube, a second valve between the point of communication and the inlet of the exhaust tube and in one position thereof partially closing the tube, a third valve element within the tube between the last named valve element and the inlet of the exhaust tube, said valves and valve element being of the butterfly type and having the stems thereof connected for simultaneous similar movement, said valve element constituting only that portion of the butterfly valve against which gases moving from the inner to the exhaust of the tube exert pressure to move the element to the closed position.

4. In combination with an exhaust tube, a muffler associated therewith, an outlet for the tube to the atmosphere independent of said muffler, a valve controlling said outlet and exhaust operated means for maintaining said valve in closed position.

5. In combination, an exhaust tube, a muffler communicating with the tube intermediate the ends of the tube, a valve between the point of communication and the outlet of the exhaust tube and in one position thereof closing the tube and exhaust operated means for urging said valve to closed position.

6. In combination, an exhaust tube, a muffler communicating with the tube intermediate the inlet and outlet ends of the tube, a valve between the point of communication and the outlet of the exhaust tube and in one position thereof closing the tube, a second valve between the point of communication and the inlet of the exhaust tube and in one position thereof partially closing the tube and exhaust operated means for simultaneously shifting said valves to said positions.

In testimony whereof I hereunto affix my signature.

JOSEPH C. BEERY.
